DESIGN FOR A BOTTLE CASING

Guy T. Gibson, New Rochelle, N. Y., assignor to Guy T. Gibson, Incorporated, New York, N. Y., a corporation of New York

Application December 14, 1934, Serial No. 54,426

Term of patent 7 years

To all whom it may concern:

Be it known that I, Guy T. Gibson, a citizen of the United States, and resident of New Rochelle, in the county of Westchester and State of New York, have invented a new, original, and ornamental Design for a Bottle Casing, of which the following is a specification, reference being had to the accompanying drawing, forming a part thereof:

The figure represents a perspective view of a bottle casing, showing my new design.

The design is repeated around the entire surface of the casing.

I claim:

The ornamental design for a bottle casing, substantially as shown and described.

GUY T. GIBSON.
